[57] ABSTRACT

Several bucket brigade devices respectively constituting signal delay paths are supplied with one common sound signal obtained from one electric musical instrument such as an electronic organ or electric guitar or are separately supplied with different sound signals derived from one or more electrical musical instruments. Each of the bucket brigade devices receives the sound source signal, transmits the signal therethrough with a delay which is in accordance with the clock pulse applied thereto from a clock pulse oscillator and gives out a time-delayed signal. The delaying time is determined by the clock pulse frequency of 40 kHz to 120 kHz which is controlled by a plurality of first low frequency signals having a frequency of about 0.5 to 3 Hz and a second low frequency signal having a frequency about 5 to 12 times that of the former signal and a voltage level equal to about 1/3 to 1/5 of that of the former signal. The first low frequency signals applied to the respective clock pulse oscillators are different in phase from one another. Sound signals from the bucket brigade devices are conducted through amplifiers to one or more loudspeakers, thereby reproducing musical sounds from the loudspeakers with a unique orchestra or chorus effect.

**ENSEMBLE EFFECT IMPARTING DEVICE USING
A BUCKET BRIGADE DEVICE FOR AN ELECTRIC
MUSICAL INSTRUMENT**

This invention relates to a sound reproducing system using a bucket brigade device such as a charge coupled device and more particularly to an ensemble effect imparting device suitable for electrical musical instruments.

Various electrical musical instruments such as an electronic organ or electric guitar are generally designed to produce musical tones with tone colors which are as truthful as possible to those of a desired natural musical instrument or further with various effects such as tremolo, vibrato, reverberation or sustain. However, such conventional electrical musical instruments produce only monotonic musical sounds, failing to provide such a broad range of sounds as is offered by an orchestra or chorus, even when the musical sounds are given forth through a plurality of loudspeakers.

It is accordingly the object of this invention to provide a sound reproducing system equipped with a bucket brigade device adapted for use with electrical musical instruments which displays the unique effect of broadening the range of reproduced musical sounds.

SUMMARY OF THE INVENTION

A sound reproducing system according to the preferred embodiment of this invention is characterized in that it includes several bucket brigade devices acting as timevariable signal delay paths which produce musical sounds almost equally displaced in phase from each other with a time delay varying continuously from about 1 to 3 milliseconds under control of a first low frequency signal having a frequency of about 0.5 to 3 Hz and a second low frequency signal having a frequency about 5 to 12 (preferably 5 to 10) times that of the former signal and a voltage level equal to about 1/3 to 1/5 to that of said former signal. The bucket brigade devices are supplied with sound signals obtained from an electrical musical instrument such as an electronic organ or electric guitar and musical sounds derived from the bucket brigade devices are introduced into one or more loudspeakers for making audible.

A sound reproducing system arranged as described above has the advantage of reproducing from the loudspeakers monotonic sounds generated by an electrical musical instrument under the condition in which the range of sounds is sufficiently broadened to attain the effect of an orchestra or chorus.

A sound reproducing system according to a second embodiment of the invention enables sound signals derived from the bucket brigade devices to be combined in a proper ratio and reproduced from loudspeakers in a closer relationship, namely, offering an orchestral effect of causing musical sounds reproduced from the respective loudspeakers to present an unobstructed continuous mass of sounds.

A sound reproducing system according to a third embodiment of the invention forms the second low frequency signal by passing a white noise signal from a white noise source through a low pass filter, thereby enabling musical sounds to be reproduced from loudspeakers in a state changeable at random.

In a sound reproducing system according to a fourth embodiment of the invention, the time delays of the bucket brigade devices are more delicately controlled

by a third low frequency signal having a frequency about twice that of the first low frequency signal and substantially the same voltage level as that of the second low frequency signal, thereby reproducing musical sounds from the loudspeakers in a more delicately varying state.

In a sound reproducing system according to a fifth embodiment of the invention, sound signals from an electrical musical instrument are supplied to a low pass filter, band pass filter and high pass filter at the same time. Outputs from at least the band pass filter and high pass filter are conducted to the corresponding bucket brigade devices, offering the advantage of attaining a more stereophonic reproduction from loudspeakers with musical sounds more clearly distinguished with respect to the high, medium and low compasses.

In a sound reproducing system according to a sixth embodiment of the invention, the bucket brigade devices are separately supplied with sound signals from different electrical musical instruments or those from the upper and lower manual keyboards and/or the pedal keyboard of a single electronic organ, displaying a more prominent orchestral or chorus effect.

A sound reproducing system according to a seventh embodiment of the invention comprises two stages of the above-mentioned bucket brigade devices, enabling musical sounds to be reproduced from the loudspeakers in a more intricately varied state.

BRIEF DESCRIPTION OF THE DRAWINGS

FIG. 1 shows a block circuit diagram of a sound reproducing system according to an embodiment of the invention;

FIG. 2 illustrates the waveforms of combined first and second low frequency signals impressed on the respective voltage control oscillators shown in FIG. 1;

FIGS. 3 and 4 show the practical arrangements of different electrical musical instruments which constitute the sound source of FIG. 1;

FIGS. 5A and 5B jointly show the practical arrangement and the operational principle of each bucket brigade device shown in FIG. 1;

FIG. 6 shows another practical arrangement of the bucket brigade device;

FIG. 7 is the practical arrangement of a circuit portion including each voltage control oscillator shown in FIG. 1;

FIG. 8 shows a schematic curve diagram of the time delay characteristic of musical sounds emanated from each loudspeaker shown in FIG. 1;

FIG. 9 is the practical arrangement of a circuit portion including the low frequency oscillator and the phase shifters cascade-connected thereto shown in FIG. 1;

FIG. 10 is a front view, partly broken, of an electronic organ used as the sound source of FIG. 1;

FIGS. 11 and 13 are block circuit diagrams of different modifications of the sound reproducing system in accordance with the invention;

FIG. 14 shows a connection diagram of the sound reproducing system where an electronic organ shown in FIG. 3 is used as the sound source of FIG. 1;

FIGS. 15 to 17 shown block circuit diagrams of different sound reproducing systems embodying the invention;

FIGS. 18 and 19 are connection diagrams of the modifications of FIG. 17;

FIGS. 20 to 23 show block circuit diagrams of further different sound reproducing systems in accordance with the invention;

FIG. 24 is a connection diagram of one modification of FIG. 23;

FIGS. 25 and 26 show block circuit diagrams of sound reproducing systems according to still further embodiments of the invention; and

FIGS. 27 and 28 show different schematic arrangements, each used as the first to third sound sources of FIG. 26.

DETAILED DESCRIPTION OF ILLUSTRATED EMBODIMENTS

A sound reproducing system using a bucket bridge device in accordance with this invention will now be described by reference to the appended drawings.

FIG. 1 is a schematic block circuit diagram of a sound reproducing system embodying this invention. Reference numeral 11 denotes a sound source constituted by the later described electrical musical instrument such as an electronic organ or electric guitar. Sound signals from the sound source 11 are simultaneously supplied to a plurality of, for example, three signal delay paths respectively constituted by bucket brigade devices 12A, 12B and 12C (abbreviated as BBD in figures) of the later described arrangement. A first low frequency signal oscillator 13 for producing a first low frequency signal having a frequency of 0.5 to 1Hz (in this embodiment 0.7 Hz) and a second low frequency signal oscillator 14 for developing a second low frequency signal having a frequency about 10 times (in this embodiment 7 Hz) that of an output from the first oscillator 13 each form three signal components which are shifted in phase from each other to a substantially equal extent, for example, 60° by phase shifters 151, 152 and 161, 162 respectively. Of the two groups of said three signal components, the signal components having the same phase are mixed together, as described below, to provide three kinds of low frequency signals e1, e2 and e3 different in phase. These three kinds of combined low frequency signals of 0.7 Hz and 7 Hz are supplied to the corresponding clock pulse oscillators or shift pulse oscillators constituted by voltage controlled oscillators (abbreviated as VCO in FIG. 1) 17A, 17B and 17C so as to control their oscillation frequencies, the frequencies being in the super audible region. Sound signals supplied from the sound source 11 are delayed by the prescribed length of time determined by the clock pulse frequencies from the voltage controlled oscillators 17A to 17C and conducted to loudspeakers 19A, 19B and 19C via the corresponding amplifiers 18A, 18B and 18C. Thus the aforesaid three bucket brigade devices 12A to 12C act as time-variable signal delay paths.

Three mixtures e1, e2 and e3 of low frequency signals of 0.7 Hz and 7 Hz which are respectively supplied to the three voltage controlled oscillators 17A to 17C are shifted 60° in phase from each other as shown in FIG. 2. The first low frequency oscillator 13 produces a signal component e11 of 0.7 Hz and the other two signal components e12 and e13 having the same frequency through the phase shifters 151 and 152 with phases of 60° and 120° respectively. These signal components e11 to e13 of 0.7 have voltage levels about 3 to 5 times (3 times in this embodiment) those of the three signal components e21, e22 and e23 of 7 Hz ob-

tained from the second low frequency signal oscillator 14, the last two of which are produced with phases of 60° and 120° respectively through phase shifters 161 and 162.

For this purpose, the aforesaid signal components e11 to e13 are conducted through the corresponding resistors R1, R2 and R3 each having a value of 10 kΩ, while the signal components e21 to e23 are transmitted through the corresponding resistors R11, R12 and R13 each having a value of 30 kΩ. Thereafter, the signal components having the same phase are combined as e11 with e21, e12 with e22 and e13 with e23.

FIG. 3 is a schematic block circuit diagram of an electronic organ 111 constituting the sound source 11 of FIG. 1. The electronic organ 111 is operated by selective depression of any of the keys 22₁, 22₂ . . . 22_n arranged side by side on a keyboard 21 in the order of musical notes. Depression of a selected key produces a tone signal of a pitch corresponding to the depressed key from tone generators 24 through keyers 23. The tone signal thus produced is conducted through tone coloring filters 25 to be changed into a musical sound having the desired tone color and later is made to have a suitable volume by an expression control 27 manipulated by an expression pedal 26 and supplied to the bucket brigade devices 12A to 12C in common.

FIG. 4 schematically illustrates an electric guitar 112 constituting the sound source 11 of FIG. 1. The electric guitar 112 includes a sound box 33 connected to one end of a head 31 through an elongate neck portion 32. A finger board 34 mounted on the neck portion 32 has its upper surface fitted with a plurality of spatially arranged projecting frets 35. A plurality of strings 38 are stretched over the frets 35 by being supported at one end by tuning pegs 36 projectively provided on both sides of the head 31 and fixed on the opposite end to a wrest plank 37 disposed on the upper front part of the sound box 33. Musical sound signals generated by selective touching of the strings 38 are supplied in common to the bucket brigade devices 12A to 12C through a pickup element 39 attached to the guitar 112.

FIGS. 5A and 5B jointly illustrate a practical arrangement and the operating principle of each of the bucket brigade devices 12A to 12C of FIG. 1. The bucket brigade device 12 comprises numerous (185 in this embodiment) metal electrodes 43 having a size of, for example, 10 to 50 μm^2 substantially linearly evaporated at an interval of about 3 to 5 μm on an insulation layer 42 made of, for example, SiO_2 mounted on an N type (or P type) silicon substrate 41, and also control electrode leads 44 and 45 respectively connected to those of the above-mentioned metal electrodes 43 which are selected by leaving out the prescribed number of intervening units (alternate metal electrodes in this embodiment). When the control electrode leads 44 and 45 are impressed with a negative voltage having the same level, then depletion layers formed in those portions of the silicon semiconductor substrate 41 which are disposed immediately below the metal electrodes 43 connected to the control electrode lead 44 have a different depth from the depletion layers formed in those portions of the silicon semiconductor substrate 41 which are positioned immediately below the metal electrodes 43 connected to the control electrode lead 45 (in this embodiment, the depletion layers provided in the latter case are made deeper). In those portions of the silicon semiconductor substrate 41 which are positioned out-

side of both terminal units of the above-mentioned metal electrodes 43 are formed P type diffused regions 46 and 47 which constitute a P-N junction at the boundary facing the N type semiconductor silicon substrate 41. In this case, the P type diffused region 46 acts as an input gate and the P type diffused region 47 acts as an output gate.

On those parts of the SiO_2 insulation layer 42 which are disposed close to the P type diffused regions 46 and 47 are evaporated metal electrodes 48 and 49 acting as input and output gate electrodes respectively.

Where the bucket brigade device 12 of the above-mentioned construction is supplied with sound signals generated from the sound source 11 under the condition where the semiconductor substrate 41 is set at a zero or ground potential, and the input gate electrode 48 and the output gate electrode 49 are impressed with a proper positive voltage, and the control electrode leads 44 and 45 are alternately supplied with a control signal having a proper level of negative voltage $-V_s$ (in this embodiment, about -10 volts), then supply of a control signal to the control electrode lead 44 causes holes of minority carrier to be precharged, as shown in FIG. 5A, according to the pattern of an input sound signal, in those portions of the semiconductor substrate 41 which are disposed near the boundary facing those portions of the SiO_2 insulation layer 42 which are positioned immediately below the metal electrodes 43 connected to the control electrode lead 44. On the other hand, where the other control electrode lead 45 is supplied with a control signal (at this time, the control electrode lead 44 is not supplied with a control signal), then the precharged holes are shifted, as shown in FIG. 5B, to those portions of the semiconductor substrate 41 which are disposed near the boundary facing those portions of the SiO_2 insulation layer 42 which are positioned immediately below the metal electrodes 43 connected to the control electrode lead 45. Thereafter, the supply of a control signal alternately to the control electrode leads 44 and 45 causes an input signal conducted to the bucket brigade device 12 to be delivered therefrom with a time delay determined by the number of the linearly arranged metal electrodes 43 and the frequency of a control signal supplied alternately to the control electrode leads 44 and 45.

FIG. 6 shows another practical arrangement of each of the bucket brigade devices 12A to 12C of FIG. 1.

The bucket bridge device 121 of FIG. 6 has the same construction as that of FIGS. 5A and 5B excepting that a plurality of P type semiconductor regions 50 complementary to the N type substrate 41 are diffused in those portions of the substrate 41 which face the respective metal electrodes 43.

The bucket bridge device 121 so arranged is operated in a different manner from the bucket bridge device 12 shown in FIGS. 5A and 5B only in that the pre-charge-shift operations are executed through the P type semiconductor regions 50 when the aforesaid negative voltages are impressed on the metal electrode leads 44 and 45.

FIG. 7 shows a practical circuit arrangement of any one of the signal delay paths each including a bucket brigade device and an associated clock pulse oscillator constituted by a voltage controlled oscillator 17.

The voltage controlled oscillator 17 comprises a relaxation oscillator 51 comprised of a charging capacitor C41, a charging resistor R42, a Schmitt circuit 52

and a switching circuit 53; an oscillation frequency control circuit 54 continuously varying oscillation frequency of the relaxation oscillator 51 in response to the combined signal of 0.7 Hz and 7 Hz from the low frequency oscillators 13 and 14 or the phase shifters 151 and 161 or 152 and 162; an amplifier 55 for amplifying an output signal from the relaxation oscillator 51; a flip-flop or bistable circuit 56 triggered by an output signal from the amplifier 55; and an output circuit 57 for supplying two output signals from the bistable circuit to the corresponding one of the bucket brigade devices 12A to 12C as shift or clock pulse signals, constructed as hereinunder described respectively.

The Schmitt circuit 52 in the relaxation oscillator 51 comprises an npn transistor Q1 which has its emitter connected via a resistor R41 to a negative power source line 58N of -12 volts and its base connected to the negative power source line 58N via the capacitor C41 as well as to a grounded positive power source line 58P (hereinafter referred to as "ground") via the resistor R42; and an npn transistor Q2 having its emitter and base connected to the emitter and collector of transistor Q1, the collectors of transistors Q1 and Q2 being connected to ground via respective resistors R43 and R44.

The switching circuit 53 in the relaxation oscillator 51 comprises an npn grounded-emitter transistor Q3 having its collector connected to the base of transistor Q1 via a resistor R45 and its base connected to the collector of transistor Q2 via a resistor R46 and a parallel feedback circuit 59 comprised of a resistor R47 and a capacitor C42 as well as to the negative power source line 58N via the resistor R46 and a resistor R48.

The oscillation frequency control circuit 54 comprises an npn transistor Q4 having its emitter connected to the base of transistor Q1 via a resistor R49 and its base connected via a diode D1 of the indicated polarity to ground as well as via a coupling capacitor C43 to a variable resistor VR1 with one end connected to the ground and the other end coupled to the common output of the low frequency oscillators 13 and 14 or the phase shifters 151 and 161 or 152 and 162, said transistor Q4 acting as a voltage-controlled variable resistor.

The collector of transistor Q4 is connected to ground via a resistor R50 and also to the negative power source line 58N via a variable resistor VR2 with the variable arm connected via a resistor R51 to the base of transistor Q4. As the base voltage is varied in accordance with an a.c. signal applied through the capacitor C43, the current flowing through the transistor Q4 is varied, thereby changing the charging current to the capacitor C41.

The amplifier 55 comprises an npn grounded-emitter transistor Q5 which has its base connected via a coupling capacitor C44 to the collector of transistor Q2 as well as via a resistor R52 to the negative power source line 58N and its collector connected via a resistor R53 to ground.

The bistable circuit 56 comprises two npn grounded-emitter transistors Q6 and Q7 each having its base cross coupled to the collector of the other transistor via a parallel circuit comprising a resistor R54 or R55 and a capacitor C45 or C46 and its collector connected to ground via a resistor R56 or R57. The collectors of transistors Q6 and Q7 are also connected to the collector of transistor Q5 via individual diodes D2 and D3 of

the indicated polarities and a common coupling capacitor C47. Between the junction 60 of the diodes D2 and D3 and ground is connected a diode D4 of the indicated polarity.

The output circuit 57 comprises two npn emitter follower transistors Q8 and Q9 having their bases connected via separate resistors R58 and R59 to the collectors of transistors Q6 and Q7 and their collectors connected to the negative power source line 58N via separate resistors R60 and R61 as well as to the control electrode leads 44 and 45 of the corresponding bucket brigade device 12 or 121.

The operation of the voltage controlled oscillator 17 constructed as above-mentioned will now be described.

Firstly, when the charged voltage of the capacitor C41 reaches a predetermined value which is determined by the charging time constant of the capacitance of the capacitor C41 and the resistance of the resistor R42, then transistors Q1 and Q2 constituting the Schmitt circuit 52 are concurrently rendered conductive.

The output of the now fired transistor Q2 is fed back to the base of transistor Q3 of the switching circuit 53 through the feed back circuit 59, bringing the transistor Q3 to an ON state. Therefore, the charged voltage of the capacitor C41 is discharged through the resistor R45 and the collector-emitter path of the now conducting transistor Q3. Accordingly, the relaxation oscillator 51 develops a sawtooth signal having a frequency (in this example, less than 80 kHz) determined by the charge-discharge time constant of the capacitor C41 and the resistor R42.

Additionally, the oscillation frequency of the relaxation oscillator 51 is also affected by the emitter current of transistor Q4 constituting the frequency control circuit 54 and energized by the combined signal of 0.7 Hz and 7 Hz. As a result, the oscillation frequency of the relaxation oscillator 51 varies continuously between about 80 kHz and 240 kHz. Then, the oscillating signal from the relaxation oscillator 51 is supplied, after being amplified by the amplifier 55, to the bistable circuit 56 as a trigger signal.

The bistable circuit 56 is operated with a frequency (in this example, varying between about 40 kHz and 120 kHz) equal to $\frac{1}{2}$ of that of output signals from the relaxation oscillator 51 and produces a pair of output pulses which are different by 180° in phase. The bistable circuit 56 also acts as a wave shaper for the output signals from the relaxation oscillator 51. A pair of pulse signals having frequencies which vary continuously between 40 kHz and 120 kHz thus obtained are applied to the control electrode leads 44 and 45 of the bucket brigade device 12 as clock or shift pulses through the two emitter follower transistors Q8 and Q9 included in the output circuit 57.

As a result, sound signals from the sound source 11 supplied to the bucket brigade device 12 or 121 are delivered therefrom after a delaying time (in this example, varying, as shown in FIG. 8, between about 2.3 ms and 0.8 ms) which is determined by the frequencies of the clock pulses applied to the bucket brigade device 12 or 121 and the number of the metal electrodes 43 included therein.

Sound signals from the bucket brigade device 12 or 121 thus obtained are then conducted to the corresponding one of the amplifiers 18A to 18C through an emitter follower circuit 61 and three cascaded low pass

filters 62, 63 and 64 each having the same construction and a cutoff frequency of about 15 kHz, thereby shunting the clock pulse component included in the sound signals. The diodes D1 and D4 act to shunt the positive-going components whose level exceeds the predetermined level of the alternating signals supplied thereto.

FIG. 9 is a practical circuit arrangement of a phase shift RC oscillator 70 in accordance with the invention which can concurrently act as the low frequency oscillator 13 (or 14) and the phase shifters 151 and 152 (or 161 and 162) cascade-connected to the oscillator shown in FIG. 1.

The phase shift oscillator 70 comprises an inverter 71 which includes a grounded-emitter transistor Q having its collector connected via resistor R to the non-grounded terminal of a dc power source 72, and a positive feedback circuit 73 including a plurality of (in this example, three) RC ladder-type circuits 74, 75 and 76 connected in series between the collector of transistor Q and the base thereof.

The phase shift oscillator 70 operates with a frequency which is determined by the respective values of resistors and capacitors R71—C71, R72—C72 and R73—C73 included in the ladder-type circuits 74 to 76 and can derive from separate terminals 77, 78 and 79 three signals different by the predetermined extent in phase from each other.

According to the sound reproducing system so constructed, if the loudspeakers 19A to 19C are disposed at substantially an equal interval in a hall, room or the cabinet of an electronic organ, the sound images emanated therefrom each repeatedly rotate with a period corresponding to a 0.7 Hz component from the first low frequency oscillator 13 and can travel more minutely by adding a 7 Hz component from the second low frequency oscillator 14 to the 0.7 Hz component, attaining a unique orchestral (ensemble) or chorus effect. In an electronic organ provided with upper and lower manual keyboards 81 and 82, a pedal keyboard 83 and an expression pedal 84, for example, the upper and lower loudspeakers 19A and 19C shown in FIG. 1 are disposed on the inner walls of the left and right side panels 85 and 86 constituting the body 80 of the electronic organ and the remaining central loudspeaker 19B is positioned on the inner wall of the front panel 87.

In addition to the above-mentioned construction, as shown in FIG. 1, resistors R31, R32 and R33 each having an appropriate value, if required, are connected between the output of the central channel amplifier 18B and the output of the upper channel amplifier 18A, between the first-mentioned output and the output of the lower channel amplifier 18C, and between the second-mentioned output and the third-mentioned output. Then, parts of sound signals representing one of the respective channels are combined in a predetermined ratio with sound signals of any other channel, whereby musical sounds from the respective loudspeakers 19A to 19C are more closely correlated to each other.

FIG. 11 is a connection diagram of one modification of the sound reproducing system in accordance with the invention.

In the modification of FIG. 11, coupling circuits 91, 92 and 93 each comprising a resistor, a capacitor or an inductance coil or combinations thereof are connected between the input of the upper channel amplifier 18A and the input of the central channel amplifier 18B, be-

tween the first-mentioned input and the input of the lower channel amplifier 18C, and between the third-mentioned input and the first-mentioned input, in place of the respective resistors R31 to R33 of FIG. 1, obtaining a sound effect similar to that of FIG. 1.

FIG. 12 is a block circuit diagram of another modification of the sound reproducing system in accordance with the invention.

The modification of FIG. 12 is different from the sound reproducing system in that the outputs of the respective bucket brigade devices 12A to 12C are connected to a single loudspeaker or headphone 19 through corresponding tone coloring filters F1, F2 and F3 and variable volume controllers VR11, VR12 and VR13 provided, if required respectively, and finally through a common amplifier 18.

It is clear that the sound reproducing system of FIG. 12 is of simpler construction, but displays a less satisfactory sound effect than those of FIGS. 1 and 11.

FIG. 13 shows a connection diagram of still another modification in accordance with the invention.

In the modification of FIG. 13, three separate 0.7 Hz oscillators 131, 132 and 133 are used in place of the single 0.7 Hz oscillator 13 and the two phase shifters 151 and 152 connected in series thereto shown in FIG. 1. Similarly, the 7 Hz oscillator 14 and the two cascade-connected phase shifters 161 and 162 of FIG. 1 are replaced by three independent 7 Hz oscillators 141, 142 and 143.

The modified sound reproducing system of FIG. 13 can obtain a sound effect similar to that of the embodiment of FIG. 1, because the 0.7 Hz oscillators 131 to 133 as well as the 7 Hz oscillators 141 to 143 are ordinarily operated with different phases.

FIG. 14 is a block circuit diagram of a sound reproducing system applicable where the electronic organ 111 shown in FIG. 3 is used as the sound source 11.

Firstly, the sound reproducing system gives forth a signal of a frequency (in this example, 8.4 Hz) corresponding to that of the output signal from the aforesaid second low frequency oscillator 14 by passing an output signal from any of the tone generators 24 shown in FIG. 3 through a frequency divider 200 which comprises, for example, any number of cascaded flip-flop or bistable circuits. The 8.4 Hz signal from the frequency divider 200 is then converted through a frequency dividing counter chain 201 into three 0.7 Hz signals whose phases are different by 120°, these three 0.7 Hz signals corresponding to the output signals from the first low frequency oscillator 13 and from the two phase shifters 161 and 162. Said frequency dividing counter chain 201 is constituted by a flip-flop circuit 202, a count-by three circuit 203 connected in series thereto, and three flip-flop circuits 204, 205 and 206 connected in parallel to the three output lines of the count-by three circuit 203.

Thus, said three 0.7 Hz signals are combined through corresponding low pass filters 207, 208 and 209 with the 8.4 Hz signal obtained from the frequency divider 200 through a low pass filter 210.

The sound reproducing system so arranged according to FIG. 14 can also attain a sound effect similar to that of FIG. 1.

FIG. 15 shows a block circuit diagram of a sound reproducing system according to another embodiment of the invention.

In the embodiment of FIG. 15, a third low frequency oscillator 211 which generates a third low frequency signal having a frequency about twice (in this embodiment, 1.4 Hz) that of an output signal from the first low frequency oscillator 13 is provided in addition to the first and second low frequency oscillators 13 and 14. The first low frequency oscillator 13 is connected with a single phase shifter 15.

Thus, a combination of 0.7 Hz and 7 Hz signals from the first and second low frequency oscillators 13 and 14 is applied to the upper voltage controlled oscillator 17A; a mixture of 0.7 Hz and 7 Hz signals from the phase shifters 15 and 162 to the lower voltage controlled oscillator 17C; and a combination of 1.4 Hz and 7 Hz signals from the third low frequency oscillator 211 and the phase shifter 161 to the remaining central voltage controlled oscillator 17B.

accordingly, the central bucket brigade device 12B is subjected to a time delay modulation different from those of the upper and lower bucket brigade devices 12A and 12C, thereby effecting the following results.

That is, a sound image emanated from the central channel loudspeaker 19B coupled with the central bucket brigade device 12B repeatedly rotates with a period about twice those from the upper (left) and lower (right) channel loudspeakers 19A and 19B respectively coupled with the corresponding upper and lower bucket brigade devices 12A and 12C. Consequently, sound images from the respective loudspeaker channels become more distinct than that from any of the preceding sound reproducing systems.

FIG. 16 shows a circuit diagram of a sound reproducing system according to still another embodiment of the invention.

In the embodiment of FIG. 16, a white noise source 221 and a low pass filter 222 constructed as hereinunder described are provided in place of the second low frequency oscillator 14. The white noise source 221 comprises an npn transistor Q11 with its emitter connected to the positive pole of a dc power source 223 and its base connected to the negative pole thereof via a resistor R81, said transistor Q11 acting as a backwardly biased diode; and an amplifier 224 which includes two npn grounded-emitter transistors Q12 and Q13 connected in series and which has its input connected via a coupling capacitor C81 to the base of transistor Q11.

The low pass filter 222 comprises a resistor R82 with one end connected to the output of the amplifier 224, and a capacitor C82 with one plate connected to the other end of the resistor R82 and with the other plate connected to the positive pole of the dc power source 223. The low pass filter 222 is designed to pass only a frequency component lower than about 10 Hz of the white noise signal from the white noise source 221.

Thus, each of the bucket brigade devices 12A to 12C is subjected through the corresponding voltage controlled oscillator 17A, 17B or 17C to a time delay modulation which is determined by the mixture of the 0.7 Hz component from the first low frequency oscillator 13 or from the phase shifter 151 or 152 and the white noise component passing through the low pass filter 222.

According to the sound reproducing system of FIG. 16, the time delay of sound signals delivered from each of the bucket brigade devices 12A to 12C varies more irregularly than those of the preceding sound reprodu-

ing systems, causing sound images from the respective loudspeaker channels to travel through random courses.

FIG. 17 is a block circuit diagram of a sound reproducing system according to a further embodiment of the invention.

The sound reproducing system of FIG. 17 differs from the preceding ones in that said system has a frequency filtering means of the undermentioned construction provided between the sound source 11 and the respective bucket brigade devices 12A to 12C.

The frequency filtering means comprises a differentiation type high pass filter 231 including a capacitor C91 and a resistor R91 and designed to pass only a higher frequency component than, e.g. about 1.7 kHz; an integration type low pass filter 232 including a resistor R92 and a capacitor C92 and adapted to pass only a lower frequency component than, e.g. about 170 Hz; and a parallel resonance type band pass filter 233 including an inductance coil L and a capacitor C93.

All the filters 231 to 233 have their inputs connected in common to the sound source 11. In the embodiment of FIG. 17, the output of the high pass filter 231 is connected to the inputs of the upper and central bucket brigade devices 12A and 12B; and that of the band pass filter 233 to the inputs of the lower and central bucket brigade devices 12C and 12B.

In contrast, the output of the low pass filter 232 is connected (though it may be connected to the input of the central bucket brigade device 12B) directly to the central amplifier 18B together with the central bucket brigade device output, because the lower frequency sound signal component obtained through the low pass filter 232 is subjected to less effective time delay modulation by the bucket brigade device than the higher frequency sound signal components obtained through the high and band pass filters 231 and 233.

The sound reproducing system so arranged has the advantage of attaining a more stereophonic reproduction from the respective loudspeaker channels with musical sounds more clearly distinguished with respect to the high, medium and low compasses.

FIG. 18 shows a block circuit diagram of one modification of FIG. 17.

In the modification of FIG. 18, four bucket brigade devices 12A to 12D and four voltage controlled oscillators 17A to 17D are provided. On the other hand, the first low frequency oscillator 13 is coupled with an inverter 241 in place of the two cascaded phase shifters 151 and 152.

Similarly, the second low frequency oscillator 14 is coupled with an inverter 242 in place of the two series connected phase shifters 161 and 162.

The output of the second low frequency oscillator 14 is coupled to the upper voltage controlled oscillator 17A; that of the inverter 242 to the lower voltage controlled oscillator 17C; that of the first low frequency oscillator 13 to the central voltage controlled oscillator 17B; and that of the inverter 241 to the additional voltage controlled oscillator 17D. The output of the high pass filter 231 is connected in common to the inputs of the upper and lower bucket brigade devices 12A and 12C; that of the band pass filter 232 in common to the inputs of the central and additional bucket brigade devices 12B and 12D; and that of the low pass filter 233 (though it may be connected, for example, to the input

of the lower bucket brigade device 12C) directly to all the amplifiers 18A to 18C.

Thus, the outputs of the upper and central bucket brigade devices 12A and 12B are jointly connected to the upper amplifier 18A; those of the central and lower bucket brigade devices 12B and 12C to the central amplifier 18B; those of the lower and additional bucket brigade devices 12C and 12D to the lower amplifier 18C; and those of the additional and upper bucket brigade devices 12D and 12A to the central amplifier 18B.

A sound reproducing system of FIG. 18, modified from FIG. 17, can attain a similar sound effect.

FIG. 19 is a block circuit diagram of another modification of FIG. 17 which includes four bucket brigade devices 12A to 12D and four voltage controlled oscillators 17A to 17D, all being of the same kind as those of FIG. 18.

The modification of FIG. 19 differs from that of FIG. 18 in that: a third low frequency oscillator 250 coupled with the inverter 241 and generating a third low frequency signal of about 3 Hz is provided; the first low frequency oscillator 13 is connected in series with three phase shifters 151, 152 and 153 which deliver 0.7 Hz signals different by 90° or 60° in phase from each other; the outputs of the first and second low frequency oscillators 13 and 14 are coupled in common to the upper voltage controlled oscillator 17A, the outputs of the inverter 242 and the phase shifter 151 in common to the central voltage controlled oscillator 17B, the outputs of the third low frequency oscillator 250 and the phase shifter 152 in common to the lower voltage controlled oscillator 17C, and the outputs of the inverter 241 and the phase shifter 153 in common to the additional voltage controlled oscillator 17D; the output of the upper bucket brigade device 12A which has its input coupled to the high pass filter 231 together with that of the central bucket brigade device 12B is connected to the upper and central amplifiers 18A and 18B together with the output of the lower bucket brigade device 12C, and the output of the central bucket brigade device 12B to the central and lower amplifiers 18B and 18C together with the output of the additional bucket brigade device 12D which has its input coupled to the band pass filter 233 together with that of the lower bucket brigade device 12C; and the output of the low pass filter 232 is connected only to the central amplifier 18B.

The sound reproducing system of FIG. 19 enables sound images emanated from the respective loudspeakers 19A to 19C to travel through more complicated courses than those of FIG. 18.

Additionally, in FIG. 19, coupling circuits 251, 252 and 253 having the same construction as the coupling circuits 91 to 93 of FIG. 11 are connected between the output of the upper amplifier 18A and the input of the central amplifier 18B, between the output of the central amplifier 18B and the input of the lower amplifier 18C and between the output of the lower amplifier 18C and the input of the upper amplifier 18A.

FIG. 20 shows a block circuit diagram of a further modification of FIG. 1.

The modification of FIG. 20 differs from the embodiment of FIG. 1 in that the central amplifier 18B and the central loudspeaker 19B are omitted and the output of the central bucket brigade device 12B is supplied to the upper and lower amplifiers 18A and 18C.

FIG. 21 is a block circuit diagram of a still further modification of FIG. 1.

The modification of FIG. 21 differs from the embodiment of FIG. 1 in that: a set of bucket brigade device and voltage controlled device is omitted; the first low frequency oscillator 13 is coupled with the inverter 241 in place of the two phase shifters 151 and 152; the second low frequency oscillator 14 is coupled with the inverter 242 in place of the two phase shifters 161 and 162; the upper voltage controlled oscillator 17A is coupled with the outputs of the inverters 241 and 242; the lower voltage controlled oscillator 17B is coupled with the outputs of the first and second low frequency oscillators 13 and 14; and sound signals from the sound source 11 are supplied directly to both the amplifiers 18A and 18B in addition to both the bucket brigade devices 12A and 12B.

The modified sound reproducing systems of FIGS. 20 and 21 cause musical sounds from both the loudspeakers to vary with a more complicated mode than those of FIG. 1.

FIG. 22 shows a block circuit diagram of a sound reproducing system according to another embodiment of the invention.

In the embodiment of FIG. 22, sound signals from the sound source 11 are subjected to two steps of time delay modulation through a first or front stage of single bucket brigade device 12F and a second or rear stage of three parallel arranged bucket brigade devices 12RA, 12RB and 12RC.

The front bucket brigade device 12F is subjected to a time delay modulation by a front voltage controlled oscillator 17F coupled with the first low frequency oscillator 13, while the rear-upper bucket brigade device 12RA is subjected to a time delay modulation by a rear-upper voltage controlled oscillator 17RA coupled with the second low frequency oscillator 14; the rear-central bucket brigade device 12RB to a time delay modulation by a rear-central voltage controlled oscillator 17RB coupled with the phase shifter 161; and the rear-lower bucket brigade device 12RC to a time delay modulation by a rear-lower voltage controlled oscillator 17RC coupled with the phase shifter 162.

The sound reproducing system of FIG. 22 can also attain a sound effect similar to that of FIG. 1.

FIG. 23 shows a block circuit diagram of one modification of FIG. 22.

The modification of FIG. 23 differs from the embodiment of FIG. 22 in that said modification comprises two front bucket brigade devices 12FA and 12FC having their inputs connected in common to the sound source 11; and a single rear bucket brigade device 12RB having its input coupled with the outputs of both the front bucket brigade devices.

The front-upper bucket brigade device 12FA is subjected to a time delay modulation by a front-upper voltage controlled oscillator 17FA coupled with the first and second low frequency oscillators 13 and 14; the front-lower bucket brigade device 12FC to a time delay modulation by a front-lower voltage controlled oscillator 17FC coupled with the phase shifters 152 and 162; and the rear bucket brigade device 12RB to a time delay modulation by a rear voltage controlled oscillator 17RB coupled with the phase shifters 151 and 161.

FIG. 24 shows a connection diagram of another modification of FIG. 22.

The modification of FIG. 24 differs from that of FIG. 23 in that the central amplifier 18B and loudspeaker 19B are omitted and the output of the rear bucket brigade device 12RB is coupled to the remaining upper and lower amplifiers 18A and 18B.

FIG. 25 is a block circuit diagram of still another modification of FIG. 22.

The modification of FIG. 25 has a construction substantially equivalent to the combination of FIGS. 17 and 22 excepting that the front stage of bucket brigade device comprises two bucket brigade devices 12FA and 12FB which are subjected to time delay modulations by corresponding voltage controlled oscillators 17FA and 17FB one of which is coupled with a third low frequency oscillator 261 generating a third low frequency signal of about 4 Hz and a fourth low frequency oscillator 262 generating a fourth low frequency signal of about 14 Hz, and the other of which is coupled with two inverters 263 and 264 each connected to the corresponding third and fourth low frequency oscillators 261 and 262.

FIG. 26 shows a block circuit diagram of a sound reproducing system according to a still further embodiment of the invention.

The embodiment of FIG. 26 differs from that of FIG. 1 in that there are provided two parallel arrangements each having substantially the same construction as that of FIG. 1 and including bucket brigade devices 12FA to 12FC or 12RA to 12RC and voltage controlled oscillators 17FA to 17FC or 17RA to 17RC; and three separate sound sources 11A, 11B and 11C as hereinunder described.

Said three separate sound sources 11A to 11C may be provided, as shown in FIG. 27, by an upper manual keyboard 271, a lower manual keyboard 272 and a pedal keyboard 273 which are built in a single electronic organ as shown in FIG. 10 and which produce tone signals from tone generators 274 corresponding to the selectively depressed keys on said keyboards 271 to 273.

Said three sound sources 11A to 11C may also be provided, as shown in FIG. 28, by an electric guitar 281, an electronic organ 282 and an electric bass 283.

The sound reproducing system arranged as described above can attain a very excellent stereophonic sound effect.

What is claimed is:

1. A sound reproducing system for reproducing musical sounds from an electrical musical instrument, comprising:

at least one source of sound signals obtained during performance on at least one electrical musical instrument;

a plurality of bucket brigade devices coupled with said sound signal source to receive said sound signals, each of said bucket brigade devices acting as a signal delay path for the sound signals supplied thereto from said sound signal source;

a plurality of voltage controlled type clock pulse oscillators, each generating a clock pulse signal having a super audible frequency, coupled with a corresponding one of said bucket brigade devices to cause said bucket brigade devices to impart respective time delays to the sound signals supplied thereto from said sound signal source, the imparted time delay being a function of the frequency of the

clock pulse signal generated by the associated clock pulse oscillator; means coupled to said clock pulse oscillators to continuously vary the frequencies of the clock pulse signals generated thereby, said means for varying the frequencies of the clock pulse signals including at least two low frequency signal sources, one of said low frequency signal sources generating a first low frequency signal having a frequency of about 0.5 to 3 Hz, and the other low frequency signal source generating a second low frequency signal having a frequency of about 5 to 12 times that of said first low frequency signal and a voltage level equal to about 1/3 to 1/5 of that of said first low frequency signal; phase shift means for converting at least one of said first and second low frequency signals from said low frequency signal sources into a plurality of signals having different phases; and means coupling said low frequency signals, including said different phase signals, to said clock pulse oscillators to cause each of said bucket brigade devices to impart to the sound signals supplied thereto from said sound source a time delay which continuously varies with the frequency of the clock pulse signal from the corresponding one of said clock pulse oscillators; and means receiving said delayed sound signals obtained through said bucket brigade devices for generating an audio output responsive thereto.

2. A sound reproducing system claimed in claim 1 wherein said sound signal source is arranged to produce sound signals from a single electrical musical instrument and to supply the produced sound signals in common to said bucket brigade devices.

3. A sound reproducing system claimed in claim 2 wherein said single electrical musical instrument comprises an electronic organ having manual and pedal keyboards and which produces a plurality of different sound signals including a first signal derived by playing the manual keyboard of said electronic organ and a sound signal obtained by manipulating the pedal keyboard thereof, and said first and second sound signals are separately supplied to said bucket brigade devices.

4. A sound reproducing system claimed in claim 1 wherein said sound signal source is arranged to produce sound signals from at least two different types of electrical musical instruments, the sound signals from said different instruments being coupled to different ones of said bucket brigade devices.

5. A sound reproducing system claimed in claim 1 further including sound mixing means for combining a part of sound signals from any of said bucket brigade devices with sound signals from the other bucket brigade devices, said audio output generating means including a plurality of separate loudspeakers and being responsive to the combined sound signals from the respective bucket brigade devices to generate different audible sounds from said plurality of separate loudspeakers.

6. A sound reproducing system claimed in claim 1 wherein said means for varying includes a third low frequency signal source generating a third low frequency signal having a frequency about twice that of said first low frequency signal and a voltage level substantially equal to that of said second low frequency signal, and said third low frequency signal is coupled to said clock pulse oscillators with said first and second low fre-

quency signals such that said bucket brigade devices cause the sound signals supplied thereto from said sound source to be time-delayed with a more complicated mode.

5 7. A sound reproducing system claimed in claim 1 wherein at least one of said low frequency signal sources comprises a white noise signal source and a low pass filter coupled with said white noise signal source.

10 8. A sound reproducing system claimed in claim 1 further including at least one frequency filtering means through which sound signals from said sound signal source are supplied to said bucket brigade devices.

15 9. A sound reproducing system claimed in claim 1 wherein said low frequency signal sources comprises low frequency oscillators.

10 10. A sound reproducing system claimed in claim 1 comprising at least two groups of said bucket brigade devices, and the respective groups of said bucket brigade devices are controlled by signals having different 20 low frequencies from said low frequency signal sources through corresponding clock pulse oscillators.

15 11. A sound reproducing system claimed in claim 1 wherein said clock pulse oscillators each comprise a relaxation oscillator generating a signal of a super audible frequency; an oscillation frequency control circuit coupled with the input of said relaxation oscillator to continuously vary the oscillation frequency of the super audible frequency signal from said relaxation oscillator in response to the output signals from said low frequency oscillators; and a bistable circuit coupled with the output of said relaxation oscillator to deliver a pair of output signals different by 180° in phase which are supplied to the corresponding one of said bucket brigade devices as clock pulse signals.

30 12. A second reproducing system claimed in claim 8 including a plurality of frequency filtering means coupled to said sound signal source, the outputs of said filtering means being selectively coupled to said bucket brigade devices.

35 13. A sound reproducing system claimed in claim 12 wherein said plurality of frequency filtering means includes a high pass filter, a band pass filter and a low pass filter, all coupled to said sound signal source, and sound signals obtained through at least said high and band pass filters are coupled to corresponding bucket brigade devices.

40 14. A sound reproducing system claimed in claim 1 wherein said means for varying the frequencies of the clock pulse signals includes a plurality of low frequency signal sources which generate a plurality of said first low frequency signals, each of said first low frequency signals having different relative phases.

45 15. A sound reproducing system claimed in claim 1 wherein said second low frequency signal has a frequency of about 5 to 10 times that of said first low frequency signal.

50 16. A sound reproducing system claimed in claim 1 wherein said different phase signals are substantially equally phase-displaced relative to each other, and wherein said low frequency signals are selectively combined and respective combined signals are coupled to said clock pulse oscillators.

55 17. A sound reproducing system for reproducing musical sounds from an electrical musical instrument, comprising:

60 at least one source of sound signals obtained during performance on at least one electrical musical in-

strument, said at least one electrical musical instrument including an electronic organ which has a plurality of tone generators each producing a tone signal of a predetermined frequency; 5
 a plurality of bucket brigade devices coupled with said sound signal source to receive said sound signals, each of said bucket brigade devices acting as a signal delay path for the sound signals supplied thereto from said sound signal source; 10
 a plurality of voltage controlled type clock pulse oscillators, each generating a clock pulse signal having a super audible frequency, coupled with a corresponding one of said bucket brigade devices to cause said bucket brigade devices to impart respective time delays to the sound signals supplied thereto from said sound signal source, the imparted time delay being a function of the frequency of the clock pulse signal generated by the associated clock pulse oscillator; 15
 means coupled to said clock pulse oscillators to continuously vary the frequencies of the clock pulse signals generated thereby, said means for varying the frequencies of the clock pulse signals including a frequency divider coupled to at least one of said tone generators for dividing a frequency of an output signal from at least one tone generator down to a given frequency; and a frequency dividing counter chain for dividing the frequency of an output signal from said frequency divider and for generating at least two first low frequency signals 20 which are out of phase with respect to each other, said first low frequency signals having a frequency of about 0.5 to 3 Hz, the output of said frequency divider comprising a second low frequency signal having said given frequency which is about 5 to 12 25 times that of said first low frequency signals and a voltage level equal to about 1/3 to 1/5 of that of said first low frequency signals; and means coupling said low frequency signals to said clock pulse oscillators to cause each of said bucket brigade devices to impart to the sound signals supplied thereto from said sound source a time delay which continuously varies with the frequency of the clock pulse signal from the corresponding one of said clock pulse oscillators; and 30
 means receiving said delayed sound signals obtained through said bucket brigade devices for generating an audio output responsive thereto. 35

18. A sound reproducing system for reproducing mu-

50

sical sounds from an electrical musical instrument, comprising:
 at least one source of sound signals obtained during performance on at least one electrical musical instrument; 5
 a plurality of bucket brigade device coupled with said sound signal source to receive said sound signals, each of said bucket brigade devices acting as a signal delay path for the sound signals supplied thereto from said sound signal source; 10
 a plurality of voltage controlled type clock pulse oscillators, each comprising a clock pulse signal having a super audible frequency, coupled with a corresponding one of said bucket brigade devices to cause said bucket brigade devices to impart respective time delays to the sound signals supplied thereto from said sound signal source, the imparted time delay being a function of the frequency of the clock pulse signal generated by the associated clock pulse oscillators; 15
 means coupled to said clock pulse oscillators to continuously vary the frequencies of the clock pulse signals generated thereby, said means for varying the frequencies of the clock pulse signals including at least one inverter and a plurality of series coupled RC ladder-type circuits coupled between the output of said at least one inverter and the input thereof as a positive feedback path, for generating a first low frequency signal having a frequency of about 0.5 to 3 Hz, and a second low frequency signal having a frequency of about 5 to 12 times that of said first low frequency signal and a voltage level equal to about 1/3 to 1/5 of that of said first low frequency signal, at least one of said first and second low frequency signals including a plurality of signals having different phases; and means coupling said low frequency signals, including said different phase signals, to said clock pulse oscillators to cause each of said bucket brigade devices to impart to the sound signals supplied thereto from said sound source a time delay which continuously varies with the frequency of the clock pulse signal from the corresponding one of said clock pulse oscillators; and 20
 means receiving said delayed sound signals obtained through said bucket brigade devices for generating an audio output responsive thereto.
